VACUUM CLEANER

Martin Treppenhauer, Dresden, Germany

Application July 14, 1932, Serial No. 622,563
In Germany January 2, 1932

2 Claims. (Cl. 15—17)

This invention relates to a hand-operated vacuum cleaner fitted with a pump piston.

A highly important feature in vacuum cleaners of this class is low weight to reduce the effort required in operation to a minimum. The existing types comprise a cylinder having a wooden valve bottom inserted therein and a movable piston formed by a wooden disc. The use of wooden discs increases the weight of the cleaner and its length, and it often happens, furthermore, that the wooden parts swell up and become jammed. The space for accommodating the air valves in the known types of cleaners is very small, so that these valves, owing to their smallness, cannot let much air pass and the handling of the cleaner requires therefore greater efforts, though its efficiency is very low.

According to the invention, these defects are eliminated by forming the piston and the valve bottom of the vacuum cleaner from metal, artificial rosin, or the like.

By employing sheet metal in the manufacture of these parts the weight of the latter is lowered and their overall length reduced.

To insure good packing of the piston relative to the cylinder a leather packing is preferably provided on the circumference of the piston, and closely hugs the cylinder walls.

An improvement achieved by the invention deals with the arrangement of the bearing parts for the operating handles which, together with the holding members for the front closing cap of the suction cylinder, are disposed in a common double link positioned on the outside of the cylinder. In the known devices special rings were required for placing therein the operating levers, the rings being arranged around the suction cylinder whereby the weight of the cleaner was increased.

One form of the invention is illustrated in the accompanying drawing, in which Figure 1 is a general view of the device, partly in section; Fig. 2, a side view thereof; Figs. 3 and 4 are, respectively, a side view and a top view of the double link; Fig. 5 is a longitudinal section of the device, and Fig. 6, a top view of a part of the valve bottom.

Referring to the drawing, 1 is the suction cylinder made either of metal or of artificial rosin, or the like, to save weight. The top of the cylinder 1 is fitted with the hood 2 in which the piston rod 4 is guided by means of the member 3. The lower side of the cylinder is covered by the cap 5 between which and the edges of the cylinder 1 the dust bag 6 is secured. The cap 5 has

an opening for the pipe 7 which connects the suction cylinder with the mouthpiece.

The vacuum cleaner is operated by hand by means of two levers 8 and 8' movably disposed on two sides of the cylinder 1 and connected with the piston rod 4 by the members 9 and 9' in such a way that when the levers 8 and 8' are spread apart the piston rod 4 and the piston working inside the cylinder 1 are pressed down while the piston is drawn up when the levers 8 and 8' are moved towards one another.

The levers 8 and 8' are connected with the double links 10 disposed on two sides on the outer circumference of the cylinder 1. The parts 10 are provided on their upper end with the bolts 11 about which the levers 8 and 8' move, and on their lower end with the clamps 12, 13 which hold the cap 5, the member 12 being a holding clamp gripping the edge 14 of the cap 5 and the member 13 being a lever by the displacement of which the clamp 12 can be moved away from the edge 14.

The parts 10 are screwed on to the wall of the cylinder 1. To insure stability a support 15 is arranged inside the cylinder 1, which connects the two parts 10 and protects the cylinder 1 against being compressed by the operating levers 8 and 8' at their point of bearing. The support 15 may preferably serve also as carrier for the valve bottom to render special bolting means unnecessary.

Figs. 5 and 6 show the construction of the valve bottom and piston. The piston consists of a sheet metal part 16 provided with an annular depression of roof-like cross section. In the center of the part 16 the piston rod 4 is secured by means of the nut 11. The wall of the part 16 facing the piston rod 4 possesses the air passages 18 which may be covered by the leather flaps 19 which, according to the invention, are secured to the part 16 by the screw 17, the flaps 19 being in covering position during the suction stroke. At its outer circumference the part 16 carries a leather packing ring 20 held in position by the clamping ring 21.

22 is a protecting plate secured to the piston rod 4 above the piston 16 to prevent oil from dripping on the valves 18, 19.

The valve bottom rests on the support 15, and, like the piston, consists of a metal part 23 which is provided with an annular depression of roof-like cross section. The part 23 is secured to the support 15 by a bolt 24. 25 are air holes covered on their upper sides by the leather flaps 26 held in position by the bolt 24. 27 is a packing 55

ring between the cylinder wall 1 and the valve bottom 23.

The device functions as follows:

Assumed that the piston 16 is in its uppermost position, it will compress, during its descent, the air between the valve bottom 23 and itself, which causes the flaps 26 to close the valves 25 in the valve bottom, the compressed air escaping through the openings 18. Since a large number of openings 18 are provided, the piston can be moved without much effort.

The descent of the piston is effected by drawing apart the operating levers 8, 8'. When the piston has reached its lowermost position, the operating levers 8, 8' will be in their extreme position, whereupon they are drawn together again to cause the ascent of the piston 16, the flaps 19 closing at the same time the openings 18 and air being drawn in through the openings 25 of the valve bottom while the flaps 26 are raised. The dust contained in the air is retained by the bag 6, and the air above the piston 16 escapes through the openings 28 in the cap 2.

The piston rod 4 is guided by the member 3 made of a material which prevents remnants or lubricants from adhering to the piston rod 4 outside the cylinder 1.

The roof-like depression is inclined so that,

during the descent of the piston 16 the compressed air will exert pressure in vertical direction on the flaps 19 and thus raise them to permit unchecked escape of the air through the open valves 18, 19. The same applies to the valve bottom 23 and the valves 25, 26.

I claim:

1. In a hand-operated vacuum cleaner having a cylindrical suction chamber and a dust chamber divided by a valved bottom, a piston operating in the suction chamber, operating arms pivoted at opposite sides of said cylindrical chamber, connected by links to the piston, a bottom cap closing the dust chamber, holding means secured to the outside of the cylindrical chamber at opposite sides thereof extending longitudinally of and lying in contact with the cleaner and having upper and lower ends, said operating arms being articulated to the upper ends of said holding means for moving the piston, and holding clamps for said bottom cap at the lower ends of said holding means.

2. In a hand-operated vacuum cleaner according to claim 1, a support crossing the interior of the cylinder and connecting the holding means on the outside of the cylinder and carrying the valve bottom.

MARTIN TREPPENHAUER.
